UNITED STATES PATENT OFFICE.

NAHUM A. CANNON, OF FAIRVIEW, ALABAMA.

DESIGN FOR AN AMUSEMENT HOUSE.

Application filed November 4, 1927. Serial No. 24,009. Term of patent 14 years.

To all whom it may concern:

Be it known that I, NAHUM A. CANNON, a citizen of the United States, residing at Fairview, in the county of Jefferson and State of Alabama, have invented a new, original, and ornamental Design for Amusement House, of which the following is a specification.

In the drawings forming a part of this specification,

Figs. 1 and 2 are front and side elevations, respectively, of the amusement house.

The front part of the amusement house represents an arctic scene.

I claim:

The ornamental design for an amusement house substantially as shown and described.

In testimony whereof I, NAHUM A. CANNON, affix my signature.

NAHUM A. CANNON.
